(No Model.)

S. T. HUDSON.

CULTIVATOR.

No. 357,202.

Patented Feb. 8, 1887.

UNITED STATES PATENT OFFICE.

S. TERRY HUDSON, OF RIVERHEAD, NEW YORK.

CULTIVATOR.

SPECIFICATION forming part of Letters Patent No. 357,202, dated February 8, 1887.

Application filed August 26, 1884. Serial No. 141,521. (No model.)

To all whom it may concern:

Be it known that I, S. TERRY HUDSON, of Riverhead, county of Suffolk, and State of New York, have invented a new and valuable 5 Improvement in Cultivators; and I do hereby declare that the following is a full, clear, and exact description of the same, such as will enable others skilled in the art to which it pertains to make and use it, reference being to had to the drawings which form part of this specification.

My invention relates to riding-cultivators that have angular motion imparted to the wheels for the purpose of guiding the machine. 15 The objects of my improvements are, first, to place the guidance of the machine under control of the driver by means of a swivel-gear operated by direct-acting foot-levers, and to support the said levers, their stirrups, and the 20 feet of the driver from the pivot-bearings alone; second, to reduce the friction of the pivot-bearings, to protect said bearings from the destructive action of mud and dust, and to insure perfect lubrication of the parts under 25 all conditions; third, to effect an adjustment of the entire swivel-gear with reference to the frame, so that the distance apart of the foot-levers and stirrups may be changeable to suit the habit and convenience of the rider, and by 30 the same means change the wheels to suit wide or narrow rows; fourth, to furnish an adjustable yoke-connection, by which the parallel ism of the wheels can be maintained under different adjustments of the swivel-gear upon the 35 frame; fifth, to provide a more convenient and effective adjustment of the gangs of plows with reference to the corn-row; sixth, to simplify the construction of the controlling-lever and means for compelling the teeth to enter hard 40 ground. I attain these results by the devices shown in the accompanying drawings, in which—

Figure 1 represents a rear view of the carriage. Fig. 2 is the adjustable pivot-bearing, 45 and Fig. 3 shows the same casting as applied to the frame. Fig. 4 is the right-side pivot-spindle, with outwardly-projecting axle and inwardly-projecting foot-lever having stirrup attached. Fig. 5 is the rock-arm fitted 50 to square on the top of pivot-spindle *b* of Fig. 4. Fig. 6 shows the cultivating teeth or plows

and the relations of spring, spring-rod, sliding pressure-thimble, and the operating-lever. Fig. 7 shows the two gangs of teeth, the central row-space between, and the side brace for 55 regulating the width of said row-space and the nearness of the gangs to the corn-row.

Similar letters indicate like parts.

The frame *N* has attached at each side the casting *A*, forming the pivot-bearings, said 60 casting being bored out vertically, as shown at *a*, Fig. 2, in the form of a tube to receive the upright pivot-spindles *b*, Fig. 4. The axles *b* project outwardly from the lower end of said spindles to receive the wheels *x*. 65 To the inner side of the spindles, opposite the axles, I attach direct foot-levers *B*, projecting inwardly, having free ends, and provided at their extremities with foot-rests or stirrups for the operator's feet. By this construction 70 the free-end foot-levers, the axles, and the frame will be supported in proper position by the upright spindles, while the foot-levers, the axles, and the wheels are adapted to be easily worked by the driver in the angular manner 75 necessary to guide the machine, and the force of the driver's foot is communicated to the wheels in the most direct manner and with the least possible friction. By having the long vertical pivots in the form of a tube the important bearing-surfaces are entirely protected 80 and have the best possible construction for retaining oil.

The tubular pivot-bearings are a very essential feature in the field, where the wheels rolling in the soft earth are continually lifting and scattering dust over the machine. Thus the free, easy, alert action of the swivel-gear can always be depended on, and the operator is enabled to guide this machine promptly and 85 exactly to the corn-row, and can instantly avoid damage to the plants, should there be an irregular movement of the team. In this new form of steering-gear the friction developed and the effort required to operate are not at 90 all increased when the machine is set into deep heavy work, whereas in such a case the labor on other cultivators is greatly multiplied.

To suit the feet of the operator, as well as to suit different varieties of work, I provide that 95 the entire swivel-gear shall have a sliding adjustment upon the frame *N* by means of any

suitable form of holes and clamping-bolts, as at a^4 , Fig. 1, and at a^3 , Fig. 2. This adjustment of the part A upon the frame controls the position of stirrups, foot-levers, axles, wheels, 5 upright-spindles, and rock-arms c. Said rock-arms are fitted to squares on the top of the part b, or otherwise fixed to the same, and project in a line parallel with the wheels. The free ends of the rock-arms are then yoked together by the cross-bar D, the connection being made by removable joint pins or bolts at C, Fig. 1, said bolts entering suitable holes in the bar D. It is essential that the wheels be kept parallel. This is accomplished by varying the connections of the bar D. The adjustment of the part A upon the frame before described necessitates a corresponding adjustment between the rock-arms c. For this purpose suitable holes are provided on the said 15 bar at d, Fig. 1. Said adjusting-holes may be variously located, but should correspond with the adjustment of the swivel-gear before mentioned.

The casting A has a forearm or brace, Fig. 25 2. This brace at its fore end pivots on the fixed bolt a^2 , Fig. 3, when the rear part slides on the frame where the adjusting-bolts are located. This construction removes most of the draft-strain from the clamp-bolts and greatly 30 steadies the swivel-gear when the clamp-bolts are slackened to change the position of the parts. Much of the usual cramping and twisting of the sliding parts is prevented, and the adjustment is easily effected by a single person 35 without assistance.

The attachment of the cultivating-teeth to the carriage is shown in Fig. 6, in which O is the drop part of the frame, stiffened by the brace P. M is the joint-bolt or draw-rod, to 40 which the beams are hinged in such a manner as to permit free movement of the plows up and down by means of the operating-lever. Sidewise the gangs of teeth have adjustment with reference to the corn-row. This adjustment is limited and controlled by the side brace or braces, J, Fig. 7. One end of the brace is attached to the gangs between the draw-rod and the plows. The other end is attached with a joint or hinge to the rigid frame, preferably 45 at O, Fig. 7. Thus the free up-and-down movement of the plows is still permitted and the side motion of the plows is entirely prevented. In order to make the central row-space wide or narrow, as may be desired, I provide that the 50 brace shall have adjustable attachment to hold the gangs I I I sidewise in different positions with reference to the frame.

If desired, the brace may be reduced to the single form, instead of being made double or 55 two-pronged.

A suitable adjustment of the brace is shown at Fig. 7 in the form of a clamping-bolt, for the purpose of setting the gang at various distances from the corn-row. The function of this 60 side brace is very important in this particular class of cultivators, as the teeth are required

to obey the wheels at once when the machine is guided either to the right or left by the steering-gear heretofore described. Otherwise the teeth could not be guided closely to the 70 corn.

It will be understood that the side brace, J, is not intended to affect the relation of the teeth or plows one to another in the same gang. This latter function is performed by the 75 spreader-braces K K, Fig. 7.

To compel the action of the teeth in hard soil, and to raise the same out of engagement with the ground, I employ the spring-wound pressure-rod F, which is attached to the gang 80 below, and has its upper end placed within a sliding thimble or eye, G, attached to the lever H, Fig. 6, the construction being such that the downward pressure of the lever compresses the spring, the thimble G sliding freely on the rod, 85 as variations of the upward or downward pressure may require. The uplift of the teeth is effected by the thimble G rising to the hook at F, which enables the lever to be latched up on the quadrant, thus holding the teeth suspended 90 above the ground for traveling on the road.

Having thus described my invention, what I claim as new, and desire to secure by Letters Patent, is—

1. The casting or part A, having the tubular 95 vertical bearing a , the brace a^2 , and the attaching-arm a^3 , substantially as shown and described.

2. The lever B, having the vertical swiveling spindles b , the wheel-spindles b^2 , and the 100 stirrup b^3 , substantially as shown and described.

3. The combination, with the frame N, of the casting or part A, having the vertical bearing a , and the pivot or lever spindle B, forming the wheel-spindles, the swiveling connection to the frame, and the guiding foot-lever, 105 substantially as shown and described.

4. The combination, with the frame N, of the casting or swivel-bearing A, adjustable laterally upon said frame, the lever B, having 110 a wheel-spindle, and a vertical pivot-spindle swiveled in said bearing, the rock-arms c, and connecting-bar D, having adjustment substantially as shown and described.

5. The combination of the vertically extended pivots b , having vertical swiveling attachment to the frame, the swiveling wheels x , held vertically by said pivots, with operating foot-levers B, supported horizontally by the same means, substantially as shown and described. 115

6. The combination of the frame N, the pivot-bearing or casting A, having adjustment on said frame, with foot-stirrups b^3 , having adjustment to or from each other by means of the 120 part A, substantially as shown and described.

7. The combination, in a wheel-cultivator, with the frame N, the hangers O, and the pivoted drag-bars I, adjustable to or from each other, of the double brace J, pivoted at the 125 front end to the fixed hanger, and adjustably attached at the rear end to the movable drag- 130

bars for regulation of the central row-space, substantially as shown and described.

8. The combination, in a wheel-cultivator, of the gang-bars I I I, the lifting-rod F, connected therewith and having its upper extremity curved in the form of a hook or its equivalent, the coiled spring E, encircling said rod, the lifting-lever H, having latching means, and a sliding eye or thimble, G, fixed to said op-

erating-lever and sliding on the rod F above to the spring in such a manner that downward pressure can be exerted upon the spring or lifting force applied to the hook, substantially as set forth.
